DUAL PRESSURE CONTROL FOR REFRIGERATION SYSTEMS

George E. Seldon, Detroit, Mich.

Application December 9, 1937, Serial No. 178,867

2 Claims. (Cl. 236—92)

This invention relates to "dual pressure expansion valves" for controlling the flow of refrigerant to an evaporator or several evaporators or each of the several sections of one evaporator 5 of a compression type of refrigeration system.

There is at present a class of valves for controlling the flow of refrigerant to evaporators that is known as "thermostatic expansion valves".

Thermostatic expansion valves are designed to 10 regulate the flow of refrigerant through refrigeration systems in accordance with temperature conditions in predetermined parts of the system. The predetermined parts of the system usually are the expansion valve and the suction line of 15 the compressor. The valves are so designed that the temperature of the refrigerant in the suction line of the compressor must be a predetermined number of degrees higher than the temperature of the refrigerant at the valve, before the valve 20 will open. Since the refrigerant at the valve is at the boiling point, the requirement of additional degrees of temperature in the suction line of the compressor guarantees that the refrigerant in the suction line will be superheated and, 25 therefore, completely in the vapor phase. Because the refrigerant in the suction line of the compressor is completely in the vapor phase, it is impossible for liquid refrigerant to flow into the suction line of the compressor. This avoids 30 mechanical breakdowns that follow the presence of liquid refrigerant in the suction line of the compressor.

The pressure of the refrigerant in a refrigeration system is constantly changing as the amount 35 of heat in the liquid to be cooled changes. To adequately protect the refrigeration system from the flow of liquid refrigerant into the suction line of the compressor, it is necessary that the refrigerant in the suction line be superheated, 40 regardless of the pressure in the system. The constantly changing pressure in the system results in a constantly changing boiling point for the refrigerant and a constantly changing temperature level required to insure a superheated 45 condition of the refrigerant in the suction line of the compressor. It is, therefore, impractical to set a fixed temperature level in the suction line to assure a superheated condition of the refrigerant therein. Adequate protection for the compressor 50 can be afforded by a dual pressure expansion valve which maintains a temperature level in the suction line of the compressor that is a predetermined and constant number of degrees above the temperature level of the refrigerant at 55 the valve. Such a valve will maintain a super-

heated condition of the refrigerant in the suction line at all times, regardless of the pressures in the system. The pressure of the refrigerant at the valve is applied to one side of a diaphragm or bellows and a pressure exerted in response to 5 temperature conditions in the suction line is applied to the other side of the diaphragm. A spring or weight is connected to the diaphragm in such manner that a constant force is exerted in opposition to the pressure that is responsive to 10 the temperature conditions in the suction line of the compressor. This force, therefore, is added to the pressure exerted by the refrigerant at the valve. The pressure that is responsive to the 15 temperature conditions of the suction line, therefore, must be higher than the pressure of the refrigerant at the valve. To secure a higher pressure at the suction line, the suction line must be hotter than the valve. Since the valve will be at the boiling point, the suction line will be hotter 20 and will vaporize all of the refrigerant passing therethrough. The operation of the valve is such that until the temperature of the suction line is a predetermined number of degrees higher 25 than the temperature of the refrigerant at the valve, the valve will be closed. When the temperature of the suction line is high enough to superheat the refrigerant at the pressure and in 30 the system, the valve opens. The valve is designed to stay open as long as the temperature 35 differential between the bulb and the valve equals or exceeds a predetermined value, and is designed to close when the temperature differential fails to equal the predetermined value.

Various temperature-responsive media have 35 been used in the bulb that is situated in heat-conducting relation with the suction line of the compressor. The media which has been found to be most satisfactory is a media in both the liquid and the vapor phase during the normal temperature range of the valve, that possesses the temperature-pressure characteristics of the refrigerant. Such a media will permit the valve to stay open as long as the predetermined temperature 40 differential exists between the refrigerant at the valve and the refrigerant in the suction line of the compressor. This permits the use of full 45 evaporator capacity under all evaporator conditions. The use of such a media makes possible the use of a limited charge in the bulb. A limited charge is partially in the liquid and partially in the vapor phase during the normal temperature 50 range of the valve but the media is completely in the vapor phase when the temperature in the suction line rises above a predetermined 55

value. The particular advantage of the limited charge, as applied to dual pressure expansion valves, lies in the attainment of relatively large changes of pressure in the bulb for slight changes 5 of temperature during the normal range of operating temperatures, and the attainment of very small changes in pressure for large changes of temperature after a predetermined temperature is reached. This permits the valve to open in response 10 to increases of temperature in the suction line, until the temperature reaches a predetermined level whereupon the valve will close because the media in the vapor phase will be unable to keep pace with the rising pressure of the refrigerant 15 at the valve. The pressures exerted by the refrigerant in the suction line at temperatures above the predetermined level are so much greater than the normal operating pressure, that the motor which operates the compressor would 20 be overloaded. Such overloading can seriously injure the motor and greatly shorten its life. The use of a limited charge in the bulb prevents the opening of the valve when the temperature and pressure of the refrigerant in the evaporator 25 rise above a predetermined level.

Dual pressure expansion valves that are now being used are divided into two classes. The first class is known as the insulated fluid type. This type of valve has a bulb situated in heat-conducting relation with a portion of the suction line of the compressor, an expandable bellows within a valve casing, operating in response to pressures exerted by the bulb, that tends to open the valve, and an expandable bellows, responsive to the pressure 30 of the refrigerant in the evaporator, that tends to close the valve. There are two temperature-responsive bellows within the casing surrounding the valve that exert a force on the valve, but the two bellows must be insulated from each other. In such valves, definite temperature 35 relationships must be maintained between the bulb and the two bellows to insure continued operation of the valve.

The other type of dual pressure expansion 40 valve is known as the intimate fluid type. In this type pressure corresponding to the heat of the refrigerant in the suction line of the compressor is applied to one side of a pressure-responsive diaphragm and tends to open the valve, while the pressure exerted by the refrigerant at 45 the valve is exerted on the other side of the pressure-responsive diaphragm and tends to close the valve. This type of valve has a simpler construction than that used in the insulated type 50 valve but must still maintain definite temperature relationships between various parts of the device.

Definite temperature relationships are necessary 55 in valves in which a media partly in the liquid phase and partly in the vapor phase is used, because of several fundamental reactions. One of these is that the hottest liquid in the system exerts the controlling pressure. Another 60 is that the vapor condenses in the coolest part of the system. In expansion valves that are controlled by media in a bulb in heat-conducting relation with the evaporator, it is necessary that the hottest liquid be in the bulb. In the case of the insulated fluid type expansion valve, the only 65 liquid, in the part of the control which tends to open the valve, is situated in the bulb. The pressure-responsive bellows located in the valve casing must, therefore, be warmer than the bulb to prevent accumulation of liquid in the bellows. 70 The accumulation of liquid in the bellows would

serve to shift the control of the valve from the bulb to the valve casing, and the temperature of the latter would control. This obviously would be undesirable and, therefore, it is necessary that the bulb be cooler than the bellows. Such a requirement 75 prevents the immersion of the valve of the valve casing in the liquid to be cooled and makes it advisable to locate the bellows outside of the cooling compartment. Such a requirement 80 seriously limits the versatility and utility of this type of valve. In the case of the intimate fluid type expansion valves, the design is such that the temperature of the media on each side of the pressure-responsive diaphragm is approximately 85 the same, exclusive of outside influences. 15 Since the temperature of the refrigerant in the valve is lower than the temperature in the suction line of the compressor, the bulb is usually warmer than the media in contact with the pressure-responsive diaphragm. Since the media condenses 20 in the cooler portions of the control system, media will be found in the liquid phase next to the pressure-responsive diaphragm. In order for the control to be in the bulb where it should be, the liquid in the bulb must be hotter than the 25 liquid next to the pressure-responsive diaphragm. For this reason, the valve casing which contains the pressure-responsive diaphragm cannot be immersed in very hot liquids, because the liquid in the casing would be hotter than the liquid in the bulb, and the control would shift from the bulb to the valve casing. This condition is disadvantageous and seriously limits the utility of 30 this type of valve.

The shifting of control to which all dual pressure valves now in use are subject is undesirable 35 and makes the valves ineffective as a regulator of the flow of refrigerant in accordance with the superheat in the refrigerant in the suction line. The applicant avoids this condition by absolutely 40 confining the media in a housing in the bulb and transmitting the pressure exerted by the media to the pressure-responsive diaphragm in the valve casing by substantially heat-insensitive 45 means. Such an arrangement permanently restricts the control to the bulb, and insures the proper operation of the valve in accordance with the superheat in the refrigerant in the suction line of the compressor.

In the insulated fluid type expansion valves in 50 use, it is necessary that caution be observed in installing the bulb and valve. It is necessary that the capillary tube connecting the bulb and the valve does not touch the evaporator, since the capillary tube is filled with media. If the tube 55 were cooler than the valve or bulb, the media would condense there and might shift the control from the bulb. Such a condition has been known to exist in practice, and it endangers the safety 60 of the refrigeration equipment. The applicant avoids such a problem by transmitting pressures generated in the bulb by a substantially heat-insensitive liquid.

It is sometimes desirable to use one control for 65 a number of evaporators. With every other valve known in the prior art, such an arrangement would necessitate the re-engineering of the bulb and valve. The device of the applicant alone can use the same bulb for one or more valve casings.

It is an object then of this invention to provide 70 a refrigerant control valve responsive to the superheat of the refrigerant wherein the temperature of the valve in no wise modifies its action or limits its adaption to a restricted field.

It is another object to provide a valve adapted

to remain closed above a fixed evaporator pressure yet requiring no insulation of the power element from the rest of the valve thereby reducing its cost.

- 5 It is a further object to produce a valve and a temperature responsive bulb independent of each other for purposes of manufacture, shipping and field assembly, but complementary in actual use.
- 10 It is a further object to provide a thermostatic bulb and closed pressure control system whereby one thermostatic bulb can control more than one valve.
- 15 It is a further object to provide a valve or cluster of valves controlled by a closed hydraulic system having a hydraulic brake in the system to dampen the fluctuations of the valves.

20 Other objects will be apparent to one versed in the art from the following description and the accompanying drawing.

The drawing shows a compression type refrigeration system as applied to a cooling evaporator of two sections one of which is below the other and in a tank 39 containing water. The number 1 denotes a compressor, 2 is a condenser, 3 a reservoir, 4 a liquid refrigerant line to two dual pressure expansion valves 5 and 6 discharging into two sections 7 and 8 of the evaporator which is connected to the return manifold 9 leading to the compressor. Clamp 10 holds the master thermostatic bulb in intimate contact with the return manifold allowing the free exchange of heat between them.

The master thermostatic bulb 11 contains two chambers an inner 12 and an outer 13 separated by a pressure responsive surface which in this case is bellows 14. A casing 15 forms the outside wall and has outlet fitting 17 which is brazed to connecting pipe 18. Orifice 19 forms the connection between this chamber 13 and the tube 18. The inner chamber is charged with the volatile thermostatic fluid through tube 16 of the chamber sealing header 20 and is surrounded by the inert hydraulic liquid filling chamber 13 and passing out through the orifice 19 into the closed and sealed hydraulic control system. The orifice acts as a hydraulic brake checking the tendencies of the hydraulic liquid to respond to fluctuations set up by the needle in the valve seat. The inner chamber is charged with the volatile thermostatic fluid which is usually the same as the refrigerant used in the refrigeration system and preferably charged at a pressure lower than that corresponding to the charging temperature, thereby establishing a pressure below which the charge is partly in vapor phase and partly in liquid phase and above which it is entirely in vapor phase and the pressure no longer increases according to the characteristic vapor pressure temperature relation of the fluid but rather the laws of Boyle and Gay-Lussac. Hence within the temperature range of the valve the charge can be so adjusted in amount that a definite predetermined pressure is the maximum 65 the charge can exert and consequently the maximum that the hydraulic liquid can be subjected to and in turn can exert.

The closed hydraulic control system comprises chamber 13, tube 18, header 21, tubes 22 and 23 and the hydraulic liquid control chamber of the valves as shown in section at 25. Header 21 distributes the hydraulic control liquid to the valve or valves of the system, it also serves as a disconnecting and filling point. The tubes 18, 22 and 23 are brought to this header and there

soldered, brazed or welded together to close the control system. This can be done in the field and is a method of connecting more than one valve to a common thermostatic bulb. It will be noted that either tube 23 or 22 could be sealed off and the valve controlled thereby removed without disturbing the operation of the other valve. The number of valves that can be controlled by one master thermostatic bulb is governed by the relative size of the bellows 14 and 10 the area and movement of diaphragm 29. The closed system is charged with liquid through an opening in the header 21 normally closed by plug 24.

Filling the closed hydraulic control system with 15 the liquid is an operation that can readily be performed in the field though usually the connections will be made at the plant making the assemblies. However if necessary say to lengthen the tube connecting the bulb and the valve 20 in the field such lengthening can be accomplished by simply opening the control system brazing in the required length of tubing and re-filling the system with liquid and replacing plug 24. Heretofore such a lengthening of a tube in 25 the field was most inexpedient if not impossible, especially with vapor charged valves using the maximum operating pressure charge. Not only is it now possible to lengthen the tube in the field but also to add additional valves or thread 30 the connecting tube through a hole too small for the bulb in a fitting or evaporator wall and connect the bulb on the other side.

Since valves 5 and 6 are of identical construction it will suffice to describe one only, consider 35 6. The control liquid enters the dual pressure valve through sweat connection 26 which is the means for connecting the valve to the closed control system, and the tube 22 is solder sweated or brazed to the valve at this point. There is 40 also orifice 27 which can be a hole of very fine bore say .016 inch diameter. The orifice is a means for dampening the fluctuations and vibrations sometimes set up by the throttling action of needle valve on the orifice seat. The hydraulic liquid control chamber 25 of the valve is made of the cover 28 and the pressure responsive surface the diaphragm 29. On the other side of the diaphragm is the chamber 30 which is ported to connect with the outlet and tube 50 31 of the evaporator section 8. Housing 32 forms the other side of chamber 30. Orifice 33 opens into this chamber and has needle valve 34 placed therein and adapted to close it and regulate the size of the opening available to the 55 liquid refrigerant entering the valve through refrigerant line 4. The valve 34 can be moved off its seat by the action of the diaphragm due to pressure of the hydraulic control liquid, the action of the valve is also modified by the spring 35 with its adjustment screw 36 and this spring 35 is the means used to apply an exterior load to the pressure sensitive surface. Gasket 37 and screw 38 close the valve. In action during the refrigeration cycle, after the motor has started 60 the compressor begins to draw the refrigerant vapor out of the evaporator thus lowering the pressure. The pressure in chamber 25 has a maximum value set previously as described. There is also a small spring load opposed to the 70 opening of the valve. The pressure in chamber 25 is purposely set at a value above but near the normal operating range of the system and when the evaporator pressure reaches a point lower than that of 25 by the amount of the ex-

terior spring load the valve opens and allows liquid refrigerant to enter the evaporator from the liqui. line 4. The refrigerant vapor passing through the outlet manifold 9 cools the power element bulb reducing the pressure in chamber 12 and consequently chamber 13. If the temperature of the bulb is the same as the evaporator then the pressure in chamber 25 is approximately that of the evaporator and the valve 10 can not open due to the fluid and the refrigerant acting on the same effective area of the pressure responsive surface. The valve can only open when the pressure in chamber 25 is greater than the combined pressure of chamber 30 and 15 the spring load. But the pressures in 25 and 30 would be equal for equal temperatures so it is apparent that the spring 35 is useful to regulate the difference of temperature between the two points considered, in other words the load of the 20 spring 35 controls the superheat of the vapor. It will also be seen that each dual pressure valve in the refrigeration system can have its own superheat setting without interference from the other valves of the system and each valve can 25 be adjusted to compensate for variations of load and refrigerant head on it. It is also feasible to have several evaporators at different points similarly controlled, i. e. a valve on each evaporator and a master bulb at the outlet of one 30 of them. It will be seen for such operation the bulb containing the volatile fluid is in intimate contact with an outlet pipe leading from the evaporator which pipe with its rapidly moving refrigerant is a body having more than ample 35 thermal capacity to control the temperature of the bulb and consequently its vaporization pressure. This vaporization pressure is converted at the bulb to hydraulic pressure at practically the same value which in turn can control the 40 refrigerant flow to several evaporators through dual pressure valves. These evaporators need not be in the same refrigeration system, it is only necessary that the other system operate at a temperature so related to the master system 45 in which the bulb is located that the temperature difference comes within the range of the spring adjustment available, and the refrigerant used should be the same or have substantially similar characteristics and the evaporators should have approximately the same elevation. 50

What I claim and desire to secure by Letters Patent of the United States is:

1. A dual pressure control for a refrigeration system comprising a valve casing having an inlet for refrigerant, an outlet for refrigerant, a valve adapted to regulate the flow of refrigerant through said valve casing, a pressure-responsive diaphragm to operate the valve, means biasing the valve to closed position, means to permit refrigerant at evaporator pressure to contact one side of the diaphragm and exert pressure thereon tending to close the valve; a feeler bulb casing having an expandible bellows positioned therein and attached thereto, said feeler bulb casing 55 containing a temperature-responsive media that is partially in the liquid and partially in the vapor phase throughout the normal temperature range of the feeler bulb casing and completely in the vapor phase whenever the temperature of the feeler bulb casing rises above a predetermined level, said temperature-responsive media being adapted to exert pressure on the expandible bellows in response to the temperature in a prede-

termined portion of the refrigeration system, and a hydraulic system comprising a fluid tight chamber in the valve casing having a portion of one of its walls formed by the pressure-responsive surface, tubing connecting said fluid tight chamber and the feeler bulb casing, and a substantially heat-insensitive liquid completely filling the fluid tight chamber in the valve casing the tubing connecting the fluid tight chamber and the feeler bulb casing and that part of the feeler bulb casing not occupied by temperature-responsive media, said hydraulic system being adapted to transmit pressure from the bellows in the feeler bulb casing to the other side of the pressure-responsive diaphragm in the valve casing, such transmitted pressure tending to open the valve. 10

2. A dual pressure control for a refrigeration system comprising a valve casing having a hydraulic chamber and a refrigerant chamber therein separated by a pressure-responsive diaphragm, an inlet for refrigerant, an outlet for refrigerant, a valve adapted to regulate the flow of refrigerant through said valve casing, said pressure-responsive diaphragm being adapted to operate the valve, means biasing the valve to closed position, means to permit refrigerant at evaporator pressure to enter the refrigerant chamber and contact the pressure-responsive diaphragm and exert pressure thereon tending to close the valve; a feeler bulb casing having an expandible bellows positioned therein and attached to one end thereof, said feeler bulb casing containing a temperature-responsive media that is adapted to exert pressure on the expandible bellows in response to the temperature in a predetermined portion of the refrigeration system, said temperature-responsive media being partially in the liquid and partially in the vapor phase throughout the normal temperature range of the feeler bulb casing and completely in the vapor phase whenever the temperature of the feeler bulb casing rises above a predetermined level whereby the pressures exerted by said temperature-responsive media increase greatly for small increases in temperature during the normal temperature range of the feeler bulb casing and increase slightly for large increases in temperature whenever the temperature of the feeler bulb casing rises above a predetermined level, said expandible bellows and feeler bulb casing cooperating to permanently confine all of said temperature-responsive media within the feeler bulb casing; and a hydraulic system comprising the said hydraulic chamber in the valve casing, tubing connecting the hydraulic chamber in the valve casing with the feeler bulb casing, and a substantially heat-insensitive liquid completely filling said hydraulic chamber, the tubing connecting the feeler bulb casing with the hydraulic chamber and that part of the feeler bulb casing not occupied by temperature-responsive media, said hydraulic system being adapted to transmit pressure from the bellows in the feeler bulb casing to the other side of the pressure-responsive diaphragm in the valve casing whereby the temperature conditions at the valve casing cannot directly affect the temperature responsive media, said pressure transmitted by the hydraulic system being adapted to bias the valve to open position. 15
